DOMINOES GAME

Pio Morales Suteras, Habana, Cuba

Application July 12, 1939, Serial No. 284,121
In Cuba June 20, 1939

5 Claims. (Cl. 273—137)

This invention relates to the game called dominoes game, and it has for its object the provision of a dominoes game in which the groups of black circles or dots borne by the known dominoes game pieces are substituted by numeric symbols and in which the numeric symbols are shown in fixed position or on rotatably mounted discs which are provided with a weight which, in any upstanding position of a piece, will cause the numeric symbol to remain in a proper position permitting its reading, and in which the numeric symbol is protected from continued handling by the players by a transparent disc, thus it provides facilities for playing and gives the upper face of the piece a pleasant appearance.

Another object of the invention is to present the numbers on a characteristic colored background for each numeric symbol, which constitutes a means for checking at first view the proper numbers of each piece, thus avoiding errors frequently incurred in the placing of the pieces during the play.

A further object of the invention is to provide the pieces with a small ball mounted on the back side of each piece so that the pieces may loosely rotate or slide and escape from retaining by the players when the pieces are resting by their back side on a table or board.

The invention is described with reference to the figures of the accompanying drawings, of which:

Fig. 1 is an upper plan view of a dominoes game piece embodying my invention.

Fig. 2 is an enlarged longitudinal vertical section view of a piece on line 2—2 of Fig. 1.

Fig. 3 is a vertical cross-section view of a piece on line 3—3 of Fig. 1.

Fig. 4 is a vertical cross-section view of a piece on line 4—4 of Fig. 1.

Figs. 5, 6, 7, 8, 9 and 10 are similar views to that of Fig. 1, showing different shapes of the outline of the recesses or cavities on which the numeric symbols are shown.

Fig. 11 is a front view of a piece upstanding according to the verticality of its longest side.

Fig. 12 is a front view of the same piece upstanding according to the verticality of shortest side.

Fig. 13 is an enlarged vertical cross-section view on line 13—13 of Fig. 12.

Fig. 14 is a section view similar to Fig. 13, the piece being in laid down position, showing a modified form of support for the shaft of the disc carrying a numeral.

Fig. 15 is a partial longitudinal section view on line 15—15 of Fig. 14.

Fig. 16 is a view of the back side of a piece carrying a projecting ball for freely rotating or sliding.

Fig. 17 is a longitudinal vertical section view on the middle longitudinal line of the piece represented in Fig. 16.

This dominoes game is composed of 55 pieces shaped exactly as the dominoes game pieces known up to the present, in which the groups of black circles or dots engraved or in bas-relief on the upper face of the known pieces are substituted by numerals of the decimal system, or roman numerals, greek numerals, etc.

The numerals S are printed on discs made of a flexible material, such as paper 1, inserted within superficial recesses 2 formed in the two halves of the upper face of a piece 3 of rectangular shape similar to that of the pieces at present known, said recesses having a convex bottom 4 covered by the paper disc 1 which is protected by a disc of transparent material such as mica 5 retained within the recess 2 by a metal ring 6 press-fitted against the peripheral edge of recess 2.

The division of the upper face of piece 3 into two halves is marked by means of a metal strip 7 divided into two longitudinal halves by a metal nail 8 whose head 8' rests against the adjacent ends of the two halves of strip 7.

The contour of the recess 2 and the metal ring 6 may affect two distinct shapes: thus Figs. 1 and 10 illustrate a circular shape; Fig. 5 illustrates a triangular shape; Fig. 6 illustrates a starry shape; Fig. 7 illustrates a polygonal shape with entering and projecting portions; Fig. 8 illustrates a square shape; and Fig. 9 illustrates an octagonal shape.

The paper discs 1 will preferably be in a distinct and characteristic color for each of the nine numerals employed in the dominoes game, and thus the characteristic color of the background on which each numeral S is printed constitutes a checking means for each numeral, whereby errors in the placing of pieces during the play will be avoided.

In Figs. 11, 12 and 13 is represented a modified form of construction of a piece, wherein the numerals S are mounted on rotatory discs so that regardless of the upstanding position in which a piece is placed by the player, the numerals S will always remain in proper position for their reading. In said figures is shown a piece 3 having two cylindrical cavities 10 separated by a

solid portion 9, and in each cavity is rotatably arranged a disc 11 on whose outer face is adhered through the interposition of a felt convex disc 12 the paper disc 1 bearing printed thereon the numeral S. This numeral is visible from the outside through a disc 5 made of a transparent material, such as mica, which is held in position by the metal ring 6 press-fitted in the recess 13 formed in the peripheral edge of the cylindrical cavity 10. Each disc 11 is integral with a shaft 14 being perpendicularly to same and extending towards the bottom of cavity 11, said shaft being loosely mounted within a bush bearing 15 whose base is fitted into a cylindrical cavity 16 formed in the bottom of cavity 10, and the bush bearing 15 resting through an annular flange 15' against the bottom of cavity 10. The disc 11 carries on a place transversally aligned to the base or lower portion of the numeral S a weight 17 by means of which the numerals S will always tend to remain in upright position in any of the two vertical positions of the piece as indicated in Figs. 11 and 12.

In Figs. 14 and 15 is illustrated a modified form of support for the shaft 14 of disc 11, by means of a disc 18 in the shape of a spider fixed to the circular wall of cavity 10 on a seat 19 recessed in said wall, said disc 18 having at its middle portion a hole 20 for the passage therethrough of the shaft 14 whose lower end is rotatably supported in a cup-shaped bearing 21 fitted into a small cylindrical cavity 16' formed in the bottom of cavity 10.

In order that the dominoes game pieces may not stand in a fixed position on a table or board and may loosely rotate or slide upon being impelled by the player's hand, thus escaping from retaining action by the player, the back side of each piece 3 has at its middle portion a spherical-segment-shaped cavity 22 within which a small metal ball 23 is so lodged that it will slightly protrude from the surface of the back side of piece 3 as shown in Fig. 17, said small ball 23 resting on the head of a tack 24 thrust in the bottom of said cavity 22 and the small ball 23 being retained within the cavity 22 by means of a metal ring 25 fitted within an annular recess 26 formed in the edge of said cavity 22.

It is obvious that changes may be made in the shape of the pieces and of the cavities of each piece, as well as in the means for rotatably mounting the shaft of each disc carrying a numeral, without that by this reason it may be considered as altered the essential character of

the invention, which is such as claimed herein-after.

What I claim is:

1. A dominoes game piece having two cavities, numerals carrying discs within said two cavities, and means in each cavity to support the respective disc for rotary movement.
2. A dominoes game piece having two cavities, numerals carrying discs within said two cavities, means in each cavity to support the respective disc for rotary movement and weights carried by the two discs on a portion of the back thereof transversely corresponding to the base of the respective numeral, so that in any vertical position of the piece the weight may cause the respective numeral to remain in a straight position.
3. A dominoes game piece having two cylindrical cavities, a numeral carrying disc lodged within each of said two cavities, shafts projecting from the center of the discs into each cavity, supporting means fixed within each cavity to provide a loose rotatory motion to each disc shaft, and a weight joined to each disc at a portion of their back side aligned transversely to the base or lower portion of the numeral borne by same.
4. A dominoes game piece having two cylindrical cavities, a flat disc lodged within each of said cavities, a felt convex disc joined to the outer face of each flat disc, a paper disc bearing a numeral and adhered to each felt disc, a shaft joined to each flat disc in a position perpendicular to same and projecting inwards from its inner face, means for supporting in loose rotation each shaft within each cavity of the piece, a transparent disc fixed at its edge close to the edge of each cavity of the piece, and a weight joined to each flat disc at a portion of its back side aligned transversely to the base or lower portion of the numeral borne by same.
5. A dominoes game piece having two cylindrical cavities, a flat disc lodged within each of said cavities, a shaft joined to each flat disc in a position perpendicular to same and projecting from its inner face, a bearing fixed to the bottom of each cavity and within which is rotatably mounted each shaft, a felt convex disc adhered to each flat disc, a paper disc bearing a numeral adhered to the felt disc, a transparent disc fixed at its edge close to the edge of each cavity of the piece, and a weight joined to the back side of each flat disc at a portion aligned transversely to the base or lower portion of the numeral borne by same.

PIO MORALES SUTERAS.
